UNITED STATES PATENT OFFICE.

OTIS C. FUNDERBURK, OF DETROIT, MICHIGAN, ASSIGNOR TO DETROIT LUBRICATOR COMPANY, OF DETROIT, MICHIGAN, A CORPORATION OF MICHIGAN.

CARBURETER.

1,249,373.

Specification of Letters Patent. Patented Dec. 11, 1917.

Application filed July 21, 1916. Serial No. 110,455.

To all whom it may concern:

Be it known that I, OTIS C. FUNDERBURK, a citizen of the United States of America, residing at Detroit, in the county of Wayne 5 and State of Michigan, have invented certain new and useful Improvements in Carbureters, of which the following is a specification, reference being had therein to the accompanying drawings.

10 The invention relates to carbureters, and has particular reference to various features of construction as hereinafter set forth.

In the drawings:

15 Figure 1 is a sectional side elevation of the carbureter;

Fig. 2 is a section in a transverse plane.

A is the casing containing the mixing chamber B. C is an air valve seated to close the air inlet to said mixing chamber. D is 20 the liquid fuel supply nozzle arranged centrally of said valve.

25 In the operation of carbureters of this type there will be more or less condensation of the liquid upon the walls of the mixing chamber and connecting conduit, which when the carbureter is idling will drain back and collect in the space surrounding the air valve and its seat. When subsequently the valve is lifted from its seat, this liquid will 30 be discharged into the incoming air, forming an abnormally rich mixture which is detrimental. To avoid such objection, I have provided means for draining the liquid collecting about the seat, which as shown

35 comprises a small conduit E connecting with a recess adjacent to the seat and extending downward into a pocket F on the lower side of the air inlet conduit G. This pocket F is formed by a fitting engaging a 40 threaded aperture in the conduit G. The tube E extends downward in the pocket to near the bottom thereof, so that the liquid draining through the conduit in filling the pocket will seal the lower end of the tube.

45 With the construction just described in

operation, whenever the carbureter is idling the condensation will collect and drain into the pocket, as has been described, and will thereby avoid accumulation about the seat of the air valve C. When the carbureter 50 is again operated the vacuum produced in the mixing chamber prior to the lifting of the air valve C will cause the greater pressure of air upon the liquid in the pocket F to force it again upward through the tube E 55 and to jet it into the mixing chamber. In this way all of the cooled liquid is again drawn in and commingled with air, but the detrimental effect of discharging a large quantity of liquid into the air inlet is 60 avoided.

What I claim as my invention is:—

1. In a carbureter, the combination with a mixing chamber and an air valve seated in the air inlet to said chamber, of a conduit 65 for draining away any condensation collecting about said valve when engaged with its seat, and a pocket for receiving the drainage and for sealing therewith the lower end of said conduit, whereby said liquid will be re-discharged through said conduit into said mixing chamber when the pressure in the latter is lower than atmosphere.

2. In a carbureter, the combination with a casing having a mixing chamber and an 75 air conduit below the same, of an air valve seated in the inlet from said air conduit to the mixing chamber, a pocket communicating with said air conduit and depending therefrom, and a conduit for draining away 80 any condensation collecting above said valve when said valve is engaged with its seat, said conduit extending through the air conduit and terminating within said pocket.

In testimony whereof I affix my signature 85 in the presence of two witnesses.

OTIS C. FUNDERBURK.
